UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING CO., A CORPORATION OF PENNSYLVANIA.

FLUID-TRANSLATING DEVICE.

Application filed September 30, 1919. Serial No. 327,566.

To all whom it may concern:

Be it known that I, HENRY F. SCHMIDT, a citizen of the United States, and a resident of Pittsburgh, in the county of Allegheny and State of Pennsylvania, have made a new and useful Invention in Fluid-Translating Devices, of which the following is a specification.

This invention relates to fluid translating devices and particularly to ejectors for withdrawing condensate from condensers.

Ejectors have many advantages over ordinary condensate pumps when employed for the purpose of removing condensate, for the reason that they are simple, compact, have no moving parts, such as pistons and impellers and discharge the condensate in the hottest possible condition. However, a disadvantage of the ordinary condensate ejector is that it is not self-starting. A further disadvantage is that an open overflow connection is ordinarily provided between the ejector and the condenser, consequently the fluids passing the overflow port are subjected to the relatively low pressure existing in the condenser, and a certain amount of spilling and evaporation takes place during the normal operation of the ejector. A check valve is frequently provided in the overflow passage, but as it opens away from the ejector it does not wholly overcome the disadvantage mentioned.

An object of my invention is to produce a new and improved condensate ejector which is self-starting.

A further object is to produce a new and improved condensate ejector which is so arranged that the fluids passing the overflow port of the ejector during normal operation are not subjected to the pressure existing in the region of low pressure with which the overflow port connects.

A further object is to produce a condensate ejector having a valve controlled overflow in connection with which means are employed for increasing the closing force exerted on said valve during normal overload conditions and for materially reducing the closing force when conditions are such as to necessitate the opening of the overflow valve.

These and other objects which will be made apparent throughout the further de-

scription of my invention are attained by means of apparatus embodying the features 55 herein described and illustrated in the drawings accompanying and forming a part hereof.

In the drawings: Fig. 1 is a diagrammatic sectional view of a fluid translating device 60 embodying my invention.

Fig. 2 is a diagrammatic sectional view of a fluid translating device and illustrates a modification of my invention.

In Fig. 1, I have illustrated a condenser 65 having at its top an inlet port 6 for fluids to be condensed, hereinafter called steam, and at its bottom a condensate collecting chamber or hot well 7. As shown, the hot well 7 is in open communication with the 70 inlet of a condensate ejector 8. The ejector 8 is illustrated as consisting of a nozzle 9 and a converging diverging diffuser tube 10 arranged in the usual manner. The nozzle 9 projects into the hot well 7 at a point 75 below the normal condensate level, and the diffuser is axially aligned therewith, having its inlet located within the hot well and below the normal condensate level. The outlet of the diffuser tube 10 connects with 80 a discharge conduit 11, in which I have shown a check valve 12 for preventing a reverse flow of fluids from the discharge pipe into the ejector when the ejector "breaks", or is not in operation. Connected 85 with the pipe 11 between the check valve 12 and the outlet of the diffuser 10 is shown an overflow pipe 13 leading to the interior of the condenser 5.

In the overflow pipe 13, I have shown an 90 overflow valve 14 adapted to be controlled by a piston 15. As illustrated, the piston 15 operates in a cylinder 16 in one end of which is shown a spring 17 which tends to hold the valve 14 open. The other end 95 of the cylinder 16, I have shown connected with the discharge pipe 11 by means of a pipe or passage 18.

In operation the condensate in the hot well 7 is entrained by the jet of motive fluid discharged from the nozzle 9 and is carried into and through the diffuser 10 in the usual manner. In passing through the diffuser 10 a part of the velocity energy of the combined fluids is converted into pressure energy in a manner well known to those skilled

in the art. The pressure of the fluids as they are discharged from the diffuser 10 is transmitted by means of the passage 18 to the cylinder 16 and under normal operating conditions is sufficient to overcome the force of the spring 17 and to hold the valve 14 closed. At the time of starting up, however, the velocity head may not be sufficient to expel the condensate against external pressure, consequently the condensate is returned to the condenser through the overflow 13, the valve 14 being open under such conditions. As soon as the ejector is capable of expelling the condensate against the external pressure, the valve 14 is closed by the pressure of the condensate and consequently the discharge passage 11 is no longer subjected to pressure conditions existing within the condenser.

If the amount of condensate to be withdrawn from the condenser 5 is not equal to the minimum capacity of the ejector 8, the ejector "breaks", that is, it ceases to entrain and discharge condensate. As a result, the pressure in the discharge pipe 11 drops, the check valve 12 closes, the valve 14 is opened by the spring 17, and the pressure against which the ejector must discharge is reduced to the pressure existing in the overflow conduit 13. The valve 14 will remain open until normal operating conditions are reestablished, after which it is held closed. This is accomplished by so proportioning the strength of the spring 17 with relation to the opposing differential pressure exerted by the fluid on the piston 15 and valve 14, that the spring is just capable of opening the valve under conditions of overflow, whereas the preponderance of the closing fluid pressure over the spring is sufficient to positively hold the valve closed during normal operating conditions.

In Fig. 2, I have illustrated a condenser 19, which is equipped with a condensate ejector 20, communication between the condenser and ejector being established by means of a conduit 21. As illustrated, the ejector 20 consists of a nozzle 22, a combining tube 23 and a diffuser 24 arranged in the usual manner and having an overflow chamber 25 surrounding the adjacent ends of the combining tube 23 and the diffuser 24. The nozzle 22 is shown as an annular nozzle and I have illustrated an auxiliary nozzle 26 axially aligned with the nozzle 22 and, in effect, extending through it into the combining chamber of the ejector. As shown, the nozzle 22 receives motive fluid through an inlet port 27 and the nozzle 26 receives motive fluid, at a different pressure, if desired, through a separate pipe 28. As illustrated, the discharge of the diffuser 24 communicates with a discharge conduit 29 in which I

have shown a check valve 30 for preventing the pressure in the discharge conduit from backing up into the ejector when the latter is not in operation.

As shown, the overflow chamber 25 of the ejector communicates with the interior of the condenser 19 by means of a conduit 31. In this conduit I have illustrated an overflow valve 32, which is adapted to control communication between the chamber 25 and the condenser and which is controlled by two pistons 33 and 34 operating in axially aligned cylinders 35 and 36. The piston 33 is of greater diameter than the piston 34 and is subjected to the pressure of the fluids issuing from the ejector 20 by means of a passage 37 which connects the cylinder 35 with the discharge conduit 29. The cylinder 36 communicates with the inlet pipe 28 of the nozzle 26 through a passage 38 and consequently the piston 34 is subjected to the pressure of the motive fluid delivered to the nozzle 26. As shown, the connections are such that both fluid pressures tend to hold the overflow valve 32 in its closed position. A spring 43 is shown in the cylinder 35 below the piston 33, and is so adjusted that it is capable of opening the valve 32 in opposition to the combined fluid pressures on the pistons 33 and 34 when operating conditions are such that the velocity of the combined fluids discharged from the tube 23 is not capable of overcoming external pressure.

I have shown a valve 39 in the pipe 28, which, as illustrated, is adapted to be controlled by the longitudinal expansion and contraction of the condensate pipe 21. As illustrated, the valve 39 is connected to the pipe 21 by means of a motion multiplying device consisting of a lever 40 and a rod 41 so arranged that longitudinal movement of the pipe actuates the valve 39.

During the normal operation of the ejector 20, condensate from the condenser 19 flows through the pipe 21 to the ejector where it is entrained by the jets of motive fluid from the nozzles 22 and 26 and is discharged through the combining tube 23 and the diffuser 24 into the discharge pipe 29. Under such conditions the valve 32 in the overflow pipe 31 is held closed by the pressure of the fluids discharged from the ejector 20 acting on the piston 33, and the pressure of the motive fluid delivered to the nozzle 26 acting on the piston 34. As a result, the fluids passing through the overflow chamber are not subjected to the low pressure existing in the condenser 19.

If the supply of condensate becomes so low that the ejector "breaks," the pressure of the fluids discharged is reduced and allows the overflow valve 32 to be easily opened, so that the fluids are discharged into the condenser 19. Under these operat-

ing conditions, the small amount of condensate coming from the condenser indicates a high vacuum, and as the condensate is relatively cool, the valve 39 will be closed 5 or nearly closed, so that the auxiliary nozzle 26 will deliver little or no entraining steam. When large quantities of steam are delivered to the condenser 19, the vacuum drops to some extent and consequently the temperature of the condensate withdrawn from the condenser increases and causes the valve 39 to be opened and to thereby deliver more motive fluid to the auxiliary nozzle 26.

During normal operation, the pressure on 15 the piston 33, and in some cases on both pistons, is relatively high and consequently the overflow valve is held shut. It is therefore evident that in the apparatus illustrated, the amount of motive fluid delivered 20 to the ejector is increased when a large amount of condensate is to be withdrawn from the condenser and that the supply of motive fluid to the auxiliary nozzle 26 is partially or completely shut off when only 25 a small amount of condensate is to be withdrawn. It is also evident that the force required to open the valve 32 varies with the pressure of fluid discharged by the ejector and to some extent with the amount 30 of motive fluid delivered to the ejector.

In the apparatus illustrated, the main nozzle 22 is designed to deliver expelling steam or motive fluid all the time the ejector is in operation and is preferably supplied with low pressure steam such as that discharged from other auxiliaries. The auxiliary nozzle 26 may be termed a booster nozzle, as its function is to deliver high pressure motive fluid or an additional supply of motive fluid and to assist in expelling the condensate when the supply of condensate is relatively large.

It will be understood that the illustrations are more or less diagrammatic, and particular attention is called to the fact that the control pistons of the valve 32, (Fig. 2) are diagrammatic to facilitate illustration and that the piston 34, exposed to steam pressure will, of necessity, be very small 50 so that it will merely exert an augmenting force and will not withdraw the control from the piston 33.

This piston is, however, necessary, since it has been found that some means must be employed for increasing the resistance to overflow when a large quantity of steam is employed or when high pressure steam is employed in an ejector. Otherwise, the ejector will continually tend to "break" and it will be difficult to establish sufficient flow to overcome external resistance.

It will also be understood that the details of construction may be materially modified and that various changes, omissions, additions and substitutions may be

made without departing from the spirit and scope of the invention as set forth by the appended claims.

What I claim is:

1. In combination with a condenser, an 70 ejector for withdrawing water of condensation therefrom having an over-flow port provided therein, a passage communicating with said port and with the interior of the condenser, a valve in said passage for closing communication between said port and said condenser, and means for controlling said valve responsive to pressure at the outlet of said ejector.

2. In combination with a condenser, an 80 ejector for withdrawing water of condensation from the condenser, a passage between an overflow port of said ejector and the interior of the condenser, a valve for controlling said passage, and means for increasing the closing force on said valve under conditions of normal operation and for decreasing the closing force under conditions necessitating the opening of said 85 valve.

3. In combination with a condenser, an 90 ejector for withdrawing water of condensation from the condenser, a passage between an overflow port of the ejector and the interior of the condenser, a valve in said passage responsive to the pressure of fluid at the overflow and means responsive to an increase in pressure at the outlet of the ejector for closing the overflow passage.

4. In combination with an ejector, an 100 overflow passage communicating therewith, a valve in said passage opening in the direction of overflow of fluid therethrough, and means responsive to an increase in pressure of the fluids passing through the ejector for closing the valve.

5. In an ejector, an overflow valve opening outwardly in the direction of flow of fluid therethrough, means responsive to a decrease in pressure of the fluids passing through the ejector for opening said valve, and means responsive to an increase in pressure of the fluids for closing the valve.

6. In combination with an ejector, an 110 overflow passage, a valve in said passage opening in the direction of flow of fluid therethrough and means responsive to variations in pressure of the fluids discharged from the ejector for varying the effectiveness of the valve.

7. In combination with an ejector, an 115 overflow valve, and a piston responsive to variations in pressure of the fluids passing through the ejector for controlling the valve.

8. In an ejector, an overflow passage, and means responsive to variations in pressure of the fluids passing through the ejector for varying the resistance to discharge of fluid through the passage.

9. In an ejector, means for delivering mo-

tive fluid thereto, an overflow passage, and means responsive to an increase in the pressure of motive fluid delivered to the ejector for increasing the resistance to discharge of fluids through the overflow passage.

10. In combination with an ejector, an overflow passage communicating therewith and with a region of relatively low pressure, means responsive to an increase in pressure of the fluids passing through the ejector for closing the overflow passage, and means for opening the passage when the pressure of the fluids drops below a predetermined amount.

11. In a condenser installation, a condenser, an ejector for withdrawing condensate from the condenser and having an overflow passage communicating therewith, and means responsive to variations in pressure of the fluids passing through the ejector for varying the resistance to discharge of fluids through the overflow passage.

12. An ejector having an overflow passage communicating with a region of relatively low pressure, and means responsive to variations in pressure of the fluids passing through the ejector for preventing said fluids from being subjected to the low pressure when passing the overflow passage during normal operation of the ejector.

13. In a condenser installation, a condenser, an ejector for withdrawing condensate from the condenser, means for delivering motive fluid to the ejector, means responsive to variations in the temperature of condensate to be withdrawn from the condenser for varying the amount of motive fluid delivered to the ejector, and means for separately delivering additional motive fluid to the ejector.

14. In combination with a condenser, an ejector for withdrawing water of condensation from the condenser, a passage establishing communication between an overflow port of the ejector and the interior of the condenser, a valve for controlling said passage and pressure responsive means including means responsive to the pressure of the motive fluid delivered to the ejector for controlling the operation of said valve.

15. In combination with a condenser, an ejector for withdrawing water of condensation from the condenser, an overflow passage between the ejector and the interior of the condenser, a valve in said passage and means responsive to the pressure of the motive fluid delivered to the ejector and to the pressure of the fluid delivered by the ejector for controlling the operation of said valve.

16. In an ejector, an overflow valve, one face of which is subjected to the pressure of fluids passing through the ejector in the direction in which the valve opens, a spring stressed to open the valve, and means responsive to pressure of the fluids exerting a closing force upon the valve.

17. The combination with an ejector having a combining tube and a diffuser, of overflow ports between the combining tube and diffuser, an overflow passage communicating with said ports, and means responsive to the pressure in said overflow passage and to the pressure at the outlet of said diffuser for controlling the flow of fluid through said overflow passage.

In testimony whereof, I have hereunto subscribed my name this 29th day of September, 1919.

HENRY F. SCHMIDT.
